UNITED STATES PATENT OFFICE.

WILLIAM J. BOHAN, OF ST. PAUL, MINNESOTA.

DRAFT DEVICE FOR LOCOMOTIVES.

1,300,335.

Specification of Letters Patent.

Patented Apr. 15, 1919.

Application filed April 7, 1917. Serial No. 160,380.

To all whom it may concern:

Be it known that I, WILLIAM J. BOHAN, a citizen of the United States, residing at St. Paul, in the county of Ramsey and State 5 of Minnesota, have invented a certain new and useful Improvement in Draft Devices for Locomotives, of which the following is a full, clear, concise, and exact description, reference being had to the accompanying 10 drawings, forming a part of this specification.

This invention relates to improvements in draft devices for locomotives.

One object of the invention is to provide 15 an attachment or device for locomotives for increasing the efficiency of the locomotive by promoting a more uniform draft than now usually obtained.

Another object of the invention is to 20 provide a draft arrangement adapted for insuring a substantially uniform draft through all the fire tubes of the boiler.

In the drawing forming a part of this specification, Figure 1 shows a longitudinal 25 section of the front end of a locomotive with my improvements in connection therewith. And Fig. 2 is a vertical, transverse section, taken substantially on the line 2—2 of Fig. 1.

30 In said drawing, 10 denotes the front flue sheet of the locomotive boiler, the latter having the usual outer shell 11 and series of fire tubes 12—12. The smoke-box of the locomotive is formed in the usual 35 manner by a shell extension 13, the joint between the shell 11 and extension 13 including an interposed annular strip 14 between the over-lapped riveted edges, as clearly appears in Fig. 1. From the smoke- 40 box extends the funnel 15 in the usual manner.

My improved draft device is located in the smoke-box and, as shown, comprises what I term a draft cone A in combination 45 with a suction or exhaust fan B. The draft cone A is formed of sheet metal and has its larger end adjacent the tube sheet 10. At said end, the cone is shaped to conform to the outline of the series of fire tubes 12, 50 that is, the upper portion of the cone is somewhat flattened, as indicated at 16 in Fig. 2, whereas the lower portion is substantially truly circular, as indicated at 17. Said larger end of the cone is butted against 55 the flue sheet 10 and an air-tight joint is

formed therebetween preferably by a cement filling 18, as shown in Fig. 1. Said cone A is supported in proper position by any suitable means such as the series of 60 bracing clips 19—19, and it will be understood that the sheet metal cone A is formed of as many pieces or sections as may be necessary to produce the required shape and preferably the longitudinally extending meeting edges of adjacent sections are edge-butted and the sections secured together by 65 an over-lapped strip 20.

At its forward or smaller end, the cone A has a substantially circular mouth, as indicated at 21, and the same fits into the intake orifice or mouth 22 of the exhaust fan B. The intake mouth or orifice of the fan B is of generally flared circular form, that is, a diametrical section at any point thereof will give a true circle, the diameters of the circles varying at different 70 points. The flare of the mouth is obtained by curving the surface in such manner that a longitudinal section through the mouth will produce two opposed arcs of circles, the 75 radius of said arcs (as indicated by the reference R in Fig. 1 of the drawing) being made the same as the minimum diameter of said mouth (as indicated by the reference D in said figure.) The outlet orifice 23 of 80 the fan which extends into the funnel 15, is formed in a similar manner. This construction of the intake mouth and outlet orifice is employed inasmuch as experience has determined that it produces the maximum 85 efficiency.

The fan proper is mounted on a shaft 24 which may be rotated by any suitable means which I do not deem it necessary to illustrate and describe.

95 Where the cone A unites with the intake orifice 22 of the exhaust fan B, said orifice is preferably provided with an internal annular shoulder 25 against which the edge of the cone butts and by which a flush 100 joint is provided. The exterior joint between the intake orifice and the cone A is preferably sealed by a cement filling, as indicated at 26. The exhaust fan B is mounted on any suitable base or standard, 105 as indicated at 27, the latter being secured to the bottom of the smoke-box, as indicated in the drawing.

I claim:

In a draft device of the character de- 110

scribed, the combination with a flue sheet of a boiler and the flues associated therewith, of a hollow cone-like conduit having its larger end fitted over said flue sheet, 5 and an exhaust fan having an intake orifice in communication with said conduit at the smaller end of the latter, said intake orifice of the fan being of circular cross section and having an outwardly curved surface,

the minimum diameter of said orifice equal- 10
ing the radius of curvature of said surface.

In witness that I claim the foregoing I have hereunto subscribed my name this 22nd day of March, 1917.

WM. J. BOHAN.

Witnesses:

GEO. F. ENDICOTT,

THOS. R. WILLIAMS.
